CLAIM

The ornamental design for a toilet seat handle, as shown and described.

DESCRIPTION

FIG. 1 is a front, side perspective view of a toilet seat handle showing my new design;

FIG. 2 is a front elevation view thereof;

FIG. 3 is a rear elevation view thereof;

FIG. 4 is a top plan view thereof;

FIG. 5 is side elevation view thereof; and

FIG. 6 is a perspective view of a toilet seat handle shown in condition of use with a partial view of a toilet seat.

The broken line showing of a partial toilet seat is for illustrative purposes only and forms no part of the claimed design.
